TIME CONTROLLED VALVE OPERATING
MECHANISM

Herbert M. Reeves, Kankakee, Ill., assignor to
Florence Stove Company, Gardner, Mass., a
corporation of Massachusetts

Application March 31, 1944, Serial No. 529,011

14 Claims. (Cl. 161—9)

1

The invention relates to improvements in time controlled valve operating mechanisms.

One object of the invention is to provide a valve operating mechanism of the above general character which, by reason of its simplicity, compactness, and wide range of adjustability, is particularly suitable for use in controlling the top burners of gaseous fuel cook stoves.

Another object is to provide a time controlled mechanism which may be set selectively for automatically effecting different degrees of adjustment of a valve such as fully or partially closing the same after a predetermined lapse of time.

A further object is to provide a time controlled valve operating mechanism for use with gaseous fuel burners which does not interfere in any way with the normal manual operation of the valve, but which may be placed in control of the valve and selectively set at any time while the valve is in use to effect a change in burner operation after a predetermined timed interval.

It is also an object of the invention to provide a compactly organized time controlled valve operating mechanism, consisting of relatively few and simple parts, which is conveniently adjustable both for different degrees of valve operation and for different timed intervals and which is capable of providing automatic burner control with complete safety.

Other objects and advantages of the invention will become apparent from the following detailed description of the preferred embodiment illustrated in the accompanying drawings in which:

Figure 1 is a front elevational view of a gaseous fuel cook stove equipped with time controlled valve operating mechanism embodying the features of the invention.

Fig. 2 is a front elevational view of the mechanism with the front panel of the stove and the setting dials removed.

Fig. 3 is a plan view of the mechanism.

Fig. 4 is a sectional view taken substantially on line 4—4 of Fig. 2.

Fig. 5 is a front view of the setting dials.

Fig. 6 is a sectional view taken substantially on line 6—6 of Fig. 2.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all the modifications and alternative constructions falling within the

2

spirit and scope of the invention as expressed in the appended claims.

For purposes of illustration, the invention has been shown in the form best suited for installation in a cabinet type stove 10 for controlling one of the top burners of the stove. In the particular stove shown, each of the burners is provided with the usual shutdown valve having a rotatable stem 11 (Fig. 2) projecting forwardly through a panel 12 closing the front of the stove. A suitable knob or handle 13 on the valve stem is accessible at the front of the panel for manual operation of the valve.

The improved valve operating mechanism comprises generally an actuating member 15 biased by a spring 16 to an inactive position and capable of being set selectively in any one of a plurality of operated positions for imparting varying degrees of adjustment to the valve with which it is associated. A timing device 17, also selectively adjustable, is provided for initiating the operation of the actuator. Through the medium of a novel driving connection provided between the actuator and the valve stem 11, the actuator is enabled to operate the valve automatically when required without interfering in any way with the normal manual operation of the valve.

As herein shown, the actuator 15 is in the form of an elongated flat bar pivotally supported at one end to rock about an axis substantially parallel to the axis of the valve stem 11 and guided at its free end by an angular guide strip 19 mounted on the stove body. Pivotal support for the actuator is provided, in this instance, by a shoulder screw 20 (Fig. 2) threaded into a supporting plate 21, removably secured to a bracket 22 which is bolted or otherwise rigidly attached to a stationary part of the stove, such as an in-turned flange 23 on the lower edge of the panel 12. The biasing spring 16 is preferably connected between the flange 23 and to the actuator 15 intermediate the ends thereof, so as to yieldably urge the latter against a fixed stop 24 defining the normal or inactive position of the actuator. The stop may be of any suitable character and is suitably mounted on the plate 21.

Any suitable means may be utilized for rocking the actuator 15 from its inactive position to various operative positions whereby the spring 16 is tensioned and the actuator thus conditioned for performing its valve operating functions. As herein shown, the means provided for this purpose comprises a drum 25 rotatably mounted on a cup shaped supporting member 26 carried by a mounting bracket 27 attached to a stationary

part of the stove in back of the panel 12. A flexible driving element 28, such as a flat metal band, is anchored at one end to the drum and at the other end to the free end of the actuator as by pin 29. Rotation of the drum 25 in a clockwise direction (as viewed in Figs. 1 and 2), is thus effective to rock the actuator in the same direction.

For rotating the drum 25, a manual operating member 30, herein shown as an annular knob or ring, is secured to the drum as by suitable screws 31. The knob is arranged to project through an aperture in the stove panel 12 for convenient access from the front of the stove and is provided with suitable indicia for indicating the various set positions of the actuator.

In the particular burner control arrangement illustrated, the valve operating mechanism is arranged for effecting two different adjustments of the burner valve, in this instance to close the valve either fully or partially after it has been opened manually. Means is accordingly provided for releasably latching the actuator 15 in either of two operated positions spaced progressively farther from its normal inactive position. As herein shown, the latching means comprises an elongated lever 32 fulcrumed on the stationary bracket 27 and having one end bent outwardly (Fig. 3) to form a latch element 33 for engagement by a dog 34 carried by the actuator 15. The other end of the lever is offset laterally and extended rearwardly into operative relation to the timing device 17 which is adapted to control the position thereof as will appear presently.

The dog 34, herein shown as generally U-shaped in form, is arranged to straddle the actuator 15 and is pivotally secured thereto by a pin 35 passing through the actuator and the two legs of the dog. For cooperation with the latch element 33 in holding the actuator in the two operated positions above referred to, one leg of the dog is extended to define a latch engaging shoulder 36 spaced a substantial distance in front of the actuator. An upright extension or finger 37 on said one leg of the dog is shaped to define a second latch engaging shoulder 38 (Fig. 3) located closely adjacent the actuator. A spring 39 connected between the actuator and a lug 40 extending rearwardly from the dog, yieldably urges the dog into a position to enable the shoulders to engage the latch element 33. At the same time, the dog may rock about its pivot to permit the latch engaging shoulders to pass under the latch element when the actuator is shifted to its operated positions.

The latch engaging shoulders 36 and 38, in this instance, are spaced apart so as to enable them to engage the latch element 33 when the actuator is rocked to either of the two positions heretofore described. More particularly, the arrangement is such that the shoulder 36 engages the latch element to hold the actuator in the full line position shown in Fig. 2 when the actuator is rocked to the valve closing position. When the actuator is rocked to a position to partially close the valve, the shoulder 38 engages the latch element and acts to hold the actuator in the intermediate position shown in the broken lines in Fig. 2. Upon disengagement of the latch element, the actuator is returned to its normal inactive position, against the stop 24 by the action of the spring 16. Thus the extent of movement of the actuator by the spring 16 is dependent upon its initial setting.

The return movements of the actuator from the two operated positions are transmitted to the valve stem 11 through the medium of a novel driving connection which permits normal manual operation of the valve at all times. The driving connection, as herein shown, includes a movable member 45 adapted to be connected to the valve stem 11 and having a one way driving connection with the actuator 15.

In its preferred form, the member 45 comprises a generally triangular metal plate pivotally supported adjacent its apex by a pin 46 formed on the end of a screw 47 threaded into the supporting plate 21. As shown in Fig. 4, the member is confined between the plate 21 and the adjacent face of the bracket 22 which thus serve to support and guide the member, the plate and bracket being suitably spaced apart for this purpose by a spacing element 48.

The edge portion of the member 45, remote from its pivotal axis, is turned outwardly to form an arcuate flange 49 adapted to serve as a track for a flat metal band 50 anchored at one end to the flange 49. The other end of the band 50 is anchored to a drum 51 (Fig. 2) secured to the valve stem 11. The drum is preferably mounted on the valve stem in back of the panel 12 and is locked thereto by a set screw 52.

To provide a one way driving connection between the actuator 15 and the member 45, the latter is provided adjacent its free end with a pair of inwardly projecting lugs 53 and 54 spaced apart similarly to the spacing of the latching shoulders 36 and 38 of the dog 34. The lugs 53 and 54 are positioned for engagement by an upright finger 55 on the dog 34. The forward or leading face of the finger 55 is shaped to define an abrupt shoulder operative to engage one or the other of the lugs 53 or 54 and thus positively couple the actuator with the member 45 during the return movement of the actuator. The rear face of the finger 55 is preferably rounded or inclined to permit it to slip under the lugs in the movement of the actuator toward operated positions. The actuator may thus be set when the burner is in operation without disturbing the adjusted position of the burner valve.

In order to automatically disengage the valve operating mechanism after each operation, the member 45 is supported with its pivotal axis spaced from, in this instance below, the pivotal axis of the actuator 15 as shown in Figs. 2 and 4. Accordingly, the finger 55 is caused to slide over the lower edge of the lug 53 or 54 with which it is engaged as the actuator approaches its inactive position. The relative position of the parts at the instant of such disengagement is shown, in broken lines in Fig. 2, the arrangement being such that the member 45 is freed from connection with the actuator after predetermined movement effective to produce the desired valve setting, but before the actuator reaches its inactive position.

Timed control of the valve operating mechanism is effected by the timer 17 through the medium of the latch lever 32 which, as explained heretofore, has one end portion extended into operative engagement with the timer. For controlling the latch lever, the timing device is provided with a generally circular timing cam 60 (Figs. 2 and 6) mounted on the inner end of a rotatable hub member 61 arranged concentrically in the actuator setting ring 30 and terminating at its outer end in a manually operable knob 62. The hub member is non-rotatably secured on the square end of a timing shaft 63 adapted to be

driven by conventional clockwork enclosed within a casing 64 mounted on the supporting strap 27. The arrangement is such that the clockwork may be wound up by manually turning the hub member 61 in a clockwise direction (as viewed in Fig. 2), whereby the clockwork is rendered effective to turn the hub member back to its initial starting position at an accurately timed rate.

As will be seen by reference to Figs. 2 and 6 of the drawings, the timing cam 60 is formed with a radially opening notch 66 dimensioned to receive a pin 67 carried by and projecting laterally from the end of the lever 32 overlying the hub 61. The notch is located with respect to the hub member so that it is in a position to receive the pin when the hub member and the associated timer setting knob are in their starting or "off" position. A spring 68 (Fig. 2) acting on the lever 32 urges the pin 67 into the notch thereby rocking the lever 32 into a position to withdraw the latch element 33 from the path of the dog 34. In all other positions of the hub member, the pin 67 rides over the peripheral edge of the timing cam 60 which is thus effective to hold the lever 32 and latch element 33 in effective latching position.

To facilitate disengagement of the pin 67 from the notch 66, a second or releasing cam 70 in the form of an annular metal plate is mounted on the hub member 61 in face to face relation with the timing cam 60. The releasing cam is formed with a radially opening notch 71 substantially in alignment with the notch 66 and presenting a gradually sloping cam surface 72 at one side. Preferably, the releasing cam is non-rotatably fixed to the hub member 61 while the timing cam 60 is mounted for limited rotation relative thereto. To this end, the releasing cam 70 is provided with the pin 73 engaging in a slot 74 in the cam 60 as shown in Fig. 2. When the timer setting knob 62 is initially turned for setting the timing device 17, the releasing cam turns therewith while the timing cam remains stationary, thus enabling the cam surface 72 to cam the pin 67 outwardly from the slot 66. Continued rotation of the knob results in rotation of the timing cam 60 and the cam is carried around to the extent necessary to provide a desired interval of operation before the latch is disengaged to release the valve actuator.

In operation, the burner valve is opened manually by turning the handle 13 in a clockwise direction as viewed in Fig. 1. The member 45 moves with the valve stem, being rocked to the position shown in full lines in Fig. 2 when the valve is fully opened. Manual adjustment of the valve may be made at any time without interference from the valve operating mechanism, the member 45 following such movements of the valve and assuming a position corresponding to that of the valve setting.

With the burner in operation and the parts occupying the positions shown in the full lines in Fig. 2, the valve operating mechanism may be set selectively at any time to either fully or partially close the valve after a predetermined lapse of time. By way of example, let it be assumed that the burner is to be shut off after one half hour of operation. To condition the mechanism for performing this function at the desired time, the timing device is set by turning the knob 62 through substantially one half of a revolution, that is, until the "30" minute mark on the knob is opposite the stationary marker 75 on the stove panel. In the initial movement of the knob, the releasing cam 70 acts to cam the pin 67 out of the

notch 66 in the timing cam thereby rocking the lever 32 to the latching position. Upon completion of the adjustment of the timing device, the notch 66 of the timing cam is located in the position shown in the full lines in Fig. 2, that is, substantially diametrically opposite the pin 67 and the latter is riding on the periphery of the cam.

The actuator 15 may now be set by turning the setting ring 30 in a clockwise direction until the "Hi-to-off" indicia on the ring is in line with the stationary marker 75. This results in the movement of the actuator to the high-to-off position shown in full lines in Fig. 2 in which it is held by engagement of the shoulder 36 of the dog 34 with the latch element 33. In the movement of the actuator to such position, the finger 55 of the dog is carried beyond or to the right of the lug 53 on the member 45.

Upon release of the timer setting knob 62, the clockworks of the timer rotates the hub 61 and timing cam 60 in a counter-clockwise direction at a rate effective to return the notch 66 to the "0" or starting position at the end of a thirty minute interval. As the notch reaches the "0" position, the pin 67 drops into the notch and the latch element 33 is withdrawn from engagement with the shoulder 36 of the dog, thereby releasing the actuator to the action of its biasing spring 16. The spring accordingly returns the actuator to its inactive position and the actuator, in this return movement, operates through the driving connection provided by the finger 55 and the lug 53 to carry the member 45 along with it. The movement of the member 45 is transmitted to the valve stem 11 through the flexible band 50, thus serving to completely close the valve. Substantially at the instant of valve closure, the finger 55 rides out from under the lug 53, thus disengaging the actuator from the member 45 and freeing such member and the valve for subsequent manual operation.

In setting the mechanism for partially closing the valve, the timing device 17 is adjusted in the manner above described. The actuator setting ring 30 is turned, however, only sufficiently to rock the actuator 15 to the intermediate position, in this instance, a quarter turn to align the "Hi-to-low" indicia on the ring with the stationary mark 75. The actuator is held in this position by the shoulder 38 of the dog 34 in engagement with the latch element 33. The finger 55 of the dog is now positioned for engagement with the lug 54 of the member 45 in the return movement of the actuator. The member 45 is therefore carried a proportionately smaller distance in the return movement of the actuator and accordingly turns the valve stem 11 only enough to partially close the valve.

It will be apparent from the foregoing that the invention provides a valve operating mechanism of novel and advantageous construction capable of being set selectively for effecting different degrees of adjustment of a valve after the lapse of a predetermined adjustable timed interval.

The mechanism is simple in construction and very compact, thus particularly adapting it for the control of the top burners of gaseous fuel cook stoves. When installed in such stoves, the mechanism does not interfere in any way with the normal manual control of the burners, yet is available whenever required for automatically controlling the burners in a safe and positive manner.

I claim as my invention:

1. Time controlled mechanism for use with a

valve adapted to be opened manually, comprising, in combination, an actuator adapted to be connected to the movable member of the valve, spring means urging said actuator to an inactive position, latch means for holding said actuator in either of two operated positions, manually operable means for moving said actuator to either of said operated positions against the force exerted by said spring means, and adjustable timing means operable to disengage said latch means and thereby release said actuator for return to inactive position by said spring means, said actuator being effective in returning from one operated position to partially close the valve and in returning from the other operated position to completely close the valve.

2. Time controlled mechanism for use with a valve adapted to be opened manually, comprising, in combination, a pivoted member adapted to be connected to the movable member of the valve, an actuator biased to an inactive position and adapted to be latched in either of two operated positions, time controlled means for releasing said actuator for return to inactive position, and means providing a connection between said actuator and said pivoted member whereby said actuator is adapted to rock said member to either fully or partially close the valve depending upon the operated position from which it is released.

3. Time controlled valve operating mechanism comprising, in combination, a member biased to an inactive position, means adapted to connect said member to the movable member of a manually opened valve, manually operable means for setting said member selectively in either of two operated positions, means for holding said member in either operated position, and an adjustable timer operable to release said member for return to inactive position, said member being operative in returning from one operated position to partially close the valve and in returning from the other operated position to fully close the valve.

4. Operating mechanism for use with a valve adapted to be opened manually comprising, in combination, a pivoted member adapted to be connected with the movable member of a valve and movable therewith when the valve is opened manually, a spring biased actuator adapted to be latched in either of two selected positions in which the biasing spring is placed under tension, said actuator when released returning to an inactive position under the action of the biasing spring and acting to rock said pivoted member different amounts to either fully or partially close the valve depending upon the initial position of said lever.

5. Timing mechanism for use with a valve adapted to be opened manually comprising, in combination, valve actuating means adapted to be set selectively for either fully or partially closing the valve, a spring operatively associated with said actuating means and adapted to store up energy as an incident to the setting of the actuating means, latch means operative to hold said actuating means in either set position, and a manually adjustable timer for disengaging said latch means to free said actuating means for operation by said spring.

6. Operating mechanism for use with a valve adapted to be opened manually comprising, in combination, a pair of members supported to rock about parallel axes, means adapted to connect one of said members to the movable member of the valve, a pair of laterally spaced lugs on said

one member, a pawl carried by the other of said members engageable with either of said lugs selectively whereby said other member is enabled to rock said first member varying amounts to either fully or partially close the valve.

7. In a valve operating mechanism, in combination, an actuator pivoted adjacent one end and yieldably urged toward an inactive position, means providing an operative connection between said actuator and a valve adapted to be opened manually, a latch element disposed at one side of said actuator, and a pawl carried by said actuator having a pair of spaced shoulders engageable selectively with said latch element to hold the actuator in either of two operated positions, said shoulders being spaced apart so as to enable said actuator to partially close the valve when released from one position and to fully close the valve when released from the other position, and time controlled means for withdrawing said latch element to release said actuator.

8. Operating mechanism for use with a valve having a rotatable stem comprising, in combination, an actuator adapted to be moved through varying distances, means for transmitting the movements of said actuator to the valve stem including a member pivotally supported adjacent one end, means providing a one-way driving connection between said member and said actuator, a drum adapted to be rigidly secured to the valve stem, and a flexible band anchored at opposite ends to said drum and to be free end of said member, said band being wound on said drum when the valve stem is manually operated to initially adjust the valve and being unwound therefrom in the response to the movement of said actuator for automatically readjusting the valve.

9. Valve operating mechanism comprising, in combination, a spring biased actuator, a latch lever operable to releasably latch said lever in selected operated positions, a timing device for releasing said actuator including a member rotatable manually in one direction to set the timing device for rotating the member in the reverse direction at a predetermined timed rate, a generally circular cam rotatable with said member, a pin carried by said lever extending over said cam, said cam having a notch positioned to receive said pin upon the return of said member to its initial starting position, said pin riding over the periphery of said cam while the member is displaced from its starting position whereby to hold said lever in latching position, and spring means operative to rock said lever to releasing position when said notch is presented for the reception of said pin.

10. Valve operating mechanism comprising, in combination, a spring biased actuator, a latch lever operable to releasably latch said actuator in selected operated positions, a pin carried at one end of said lever, means for controlling the movements of said lever between latching and releasing positions including a member rotatable manually in one direction and by clockwork in the reverse directions, a pair of generally-circular cams mounted on and rotatable with said member, said cams having notches normally aligned to receive said pin and thereby permit movement of said lever to releasing position, and means providing a lost motion connection between said member and one of said cams whereby said cams may be relatively rotated to cam said pin out of said notches and thereby move said lever to latching position.

11. In a time controlled valve actuating mechanism, in combination, an actuator biased by a spring to an inactive position, a latch element, a dog carried by said actuator presenting a pair of spaced shoulders engageable selectively with said latch element to hold said actuator in either of two operated positions, means for withdrawing said latch element from engagement with said dog, and means providing an operative connection between said actuator and the valve to be operated whereby said actuator is rendered effective to impart varying degrees of adjustment to the valve depending upon the particular operated position in which it was latched.

12. In a time controlled valve actuating mechanism, in combination, an actuator biased by a spring to an inactive position, a latch element, a dog carried by said actuator presenting a pair of spaced shoulders engageable selectively with said latch element to hold said actuator in either of two operated positions, a member supported for movement with said actuator and adapted to be connected with the valve to be operated, a pair of projecting elements on said member spaced apart a distance corresponding to the spacing of the shoulders on said dog, a finger rigid with said dog positioned to engage one or the other of said spaced elements depending upon the operated position in which said actuator is held, and means for withdrawing said latch element to release said actuator to the action of its biasing spring, said actuator operating through said finger and the element engaged thereby to impart a valve adjusting movement to said member.

13. In a valve operating mechanism, a pivoted member adapted to be operatively connected with a valve, an actuator pivoted to swing about an axis substantially parallel to the axis of said member, means for rocking said actuator in a direction effective to adjust the valve, a rigid

element carried by said member, and a dog carried by said actuator having a finger engageable with said rigid element to impart the movements of said actuator to said member, the pivotal axis of said actuator and said member being spaced apart so as to cause said finger to swing free of said rigid element as said member is rocked into a position to effect a predetermined adjustment of the valve.

14. A time controlled valve closing mechanism comprising, in combination, a valve operating member movable in one direction as an incident to the opening of the valve and operable upon movement in the opposite direction to close the valve, actuating means operable to move said member in a valve closing direction, means for operatively associating said actuating means with said member in either of two positions, latch means for holding the actuating means against operation, and a timer for releasing said latch means, said valve operating member being operable by the actuating means upon release of the latch means to either fully or partially close the valve in accordance with the associated position of said actuating means.
